UNITED STATES PATENT OFFICE

1,940,638

SPOOL

Walter R. West, Hightstown, N. J., assignor to
 Hightstown Rug Company, Hightstown, N. J.,
 a corporation of Delaware

Application June 29, 1933. Serial No. 678,223

5 Claims. (Cl. 242—124)

My invention is particularly applicable to spools for holding warp yarns in Axminster looms and of the type in which the core of the spool is formed of wood and the end flanges on the core are formed of metal disks each having a metal trunnion, formed by a gudgeon, in coaxial relation with the core and extending into the latter; one of said gudgeons being cylindrical and fitted to be journaled in a bearing in the loom, and the other having means, such as a diametrical flange or slot, to be rotatably engaged by means for controlling the rotary movement of the spool. Ordinarily, such a spool core has a groove in its circumference extending from end to end thereof parallel with its axis in registry with holes in the end disks, so that when the ends of the yarn are wrapped in a single convolution around the core, said ends may be secured in position by a rod extending over them in said groove and engaged in the holes in said disks at the opposite ends thereof. Ordinarily, the end disks are primarily fixed in coaxial relation with the core by spikes on the disks which are driven into the wood at the ends of the core. However, the relative torsional stresses to which the end disks and their connecting cores are subjected ultimately twist the disks on the cores and split the latter with the spikes.

Therefore, it is the object and effect of my invention to provide means for engaging the end disks with the cores in addition to the spikes aforesaid and capable of engaging the core to such an axial extent as to prevent the core splitting under such relative torque stresses. As hereinafter described, the essential feature of my invention is the provision of metal keys of channel form, fitted in the opposite ends of the grooves in the cores, and projecting into the openings in the end disks, and means for detachably permanently securing such keys in proper engagement with the cores and disks.

My invention includes the various novel features of construction and arrangement hereinabove more definitely specified.

In said drawing, Fig. I is a diametrical sectional view of the axially opposite ends of a spool conveniently embodying my invention.

Fig. II is an end elevation of the left hand end of the spool shown in Fig. I, showing the gudgeon by which the spool is turned.

Fig. III is an elevation of the right hand end of the spool shown in Fig. I, showing the gudgeon which is merely a journal for the spool.

Fig. IV is a cross sectional view of the core

taken on the line IV, IV, in Fig. I in the direction of the arrows on said line.

Fig. V is a cross section of the wooden core intermediate of its length.

In said figures, the spool core 1 has the groove 2 in the circumference thereof extending parallel with its axis throughout its length. Said core is provided with circumferential flanges at its opposite ends by the respective disks 3 and 3', which differ only in that the latter has a cylindrical flange at its perimeter, but are alike in that they each have spikes 4 projecting inwardly therefrom into engagement with the ends of the core 1; said spikes being conveniently formed in unitary relation with the respective disks 3 by metal punched from the triangular openings 6 in said disks. Each of said disks has a partly rectangular opening 7 thus held in registry with the respectively opposite ends of said groove 2 and with an arcuate notch in the outer edge of 75 said opening 7 adapted to receive the opposite ends of the rod 8 which are detachably fitted in said groove as aforesaid.

Each of the keys 10 is of channel form, as indicated, fitted in opposite ends of the groove 2 in said core 1; each having at its outer end a flange 11 extending radially inward in contact with the outer face of the respective disk 3 and having a circular opening 12 therethrough in coaxial relation with the opening 13 in the disk 85 to receive the respective shanks 15 of the gudgeons 16 and 17, each of which is cylindrical and has at its inner end a reduced screw threaded portion 18 for engagement with respective nuts 19 which are fitted in radial openings 20 in said core.

Said gudgeon 16 has the cylindrical head 22 bearing against the outer surface of the flange 11 and provided with diametrical slots 23 in crossed relation to receive any suitable driving means for turning the spool. The double lines at the edges of said slots 23 in Fig. II merely indicate that said edges are chamfered as indicated in Fig. I, to facilitate the insertion of the driving means therein. The gudgeon 17 has 100 a head 25 with a cylindrical trunnion 28 thereon to be journaled in a suitable bearing in the loom frame.

It is to be understood that the relative torsional stresses between the end disks 3 of the 105 spools and their cores 1 are dissipated throughout the length of said keys 10 so that rupture of the spool ends by twisting movement of the spikes 4 is avoided.

However, I do not desire to limit myself to the 110

precise details of construction and arrangement herein set forth, as it is obvious that various modifications may be made therein without departing from the essential features of my invention, as defined in the appended claims.

I claim:

1. A spool for warp yarns in an Axminster loom, comprising a wooden core with a groove in the circumference thereof extending from end to end thereof parallel with the axis of said core, for detachably receiving a rod for holding the yarn on the spool; circumferential yarn retaining flanges on said spool at the opposite ends thereof formed by respective metal disks in coaxial relation with said core; each of said disks having an axial opening and an eccentric opening for registry with said groove in the core; means for holding said disks in coaxial engagement with said core, including projections extending from said disks into the opposite ends of said core; respective keys for engaging said core with said disks, each including a metal channel fitted in said groove, at respectively opposite ends of said core and extending in said eccentric openings, and each having a flange extending exterior to its disk with an axial opening therein registering with the axial opening in said disk; means for detachably securing said disks and keys in rigid relation with said core, including respective gudgeons at opposite ends of said core extending through said disks and key flanges; each of said gudgeons having a head exterior to its disk and having a screw thread at its inner end in said core; and respective nuts in said core engaging said gudgeon screw threads, said nuts extending in radial openings in said core; one of said gudgeons having means for engagement with means to rotate the spool and the other of said gudgeons having an axial trunnion.

2. A spool for warp yarns in an Axminster loom, comprising a wooden core with a groove in the circumference thereof extending from end to end thereof parallel with the axis of said core, for detachably receiving means for holding the yarn on the spool; circumferential yarn retaining flanges on said spool at the opposite ends thereof formed by respective metal disks in coaxial relation with said core; each of said disks having an axial opening; respective keys for engaging said core with said disks, each including a metal channel fitted in said groove, at respectively opposite ends of said core and extending through the respective disks, and each having a flange extending exterior to its disk with an axial opening therein registering with the axial opening in said disk; means for detachably securing said disks and keys in rigid relation with said core, including respective gudgeons at opposite ends of said core extending through said disks and key flanges; each of said gudgeons having a head exterior to its disk

and having a screw thread at its inner end in said core; and respective nuts in said core engaging said gudgeon screw threads; one of said gudgeons having means for engagement with means to rotate the spool and the other of said gudgeons having an axial trunnion.

80

3. A spool comprising a solid core; circumferential retaining flanges on said spool at the opposite ends thereof formed by respective metal disks in coaxial relation with said core; each of said disks having an axial opening and an eccentric opening; respective keys for engaging said core with said disks, each including a metal member fitted in a groove in the circumference of said core parallel with its axis, and extending through the eccentric opening in the disk, and each having a flange extending exterior to its disk with an axial opening therein registering with the axial opening in said disk; means for detachably securing said disks and keys in rigid relation with said core, including respective gudgeons at opposite ends of said core extending through said disks and key flanges; each of said gudgeons having a head exterior to its disk and having a screw thread at its inner end in said core; and respective nuts in said core engaging said gudgeon screw threads.

85

4. A spool comprising a core; circumferential retaining flanges on said spool at the opposite ends thereof formed by respective metal disks;

90

each of said disks having an axial opening and an eccentric opening; respective keys for engaging said core with said disks, each including a metal member fitted in a groove in the circumference of said core and extending in the eccentric opening in its disk, and each having a flange extending exterior to its disk with an axial opening therein registering with the axial opening in said disk; means for detachably securing said disks and keys in rigid relation with said core, including respective gudgeons at opposite ends of said core extending through said disks and key flanges; each of said gudgeons having a head exterior to its disk and having a screw thread at its inner end in said core.

100

5. In a spool, the combination with a core; of circumferential retaining flanges on said spool at the opposite ends thereof formed by respective metal disks; each of said disks having an eccentric opening; respective keys for engaging said core with said disk, each including a metal member fitted in a groove in the circumference of said core and extending through the eccentric opening in its disk, and each having a flange extending exterior to its disk with an axial opening therein; and means for detachably securing said disks and keys in rigid relation with said core, including respective screws at opposite ends of said core extending through said key flanges.
